DOOR KNOCKER

Raymond U. H. Tegner, Rockford, Ill., assignor to
Amerock Corporation, Rockford, Ill.

Filed June 1, 1971, Ser. No. 149,099

Term of patent 14 years

Int. Cl. D8—09

U.S. Cl. D8—177

FIG. 1 is a front view of a door knocker incorporating my new design.

FIG. 2 is a side view as seen from the right in FIG. 1.

FIG. 3 is a top view of the door knocker.

FIG. 4 is a bottom view.

FIG. 5 is a rear view of the door knocker.

FIG. 6 is a sectional view taken along the line 6—6 in FIG. 1.

FIG. 7 is a sectional view taken along the line 7—7 in FIG. 1.

FIG. 8 is a sectional view taken along the line 8—8 in FIG. 1.

FIG. 9 is a sectional view taken along the line 9—9 in FIG. 1.

FIG. 10 is a sectional view taken along the line 10—10 in FIG. 1.

I claim:

The ornamental design for a door knocker, as shown.
